LEWIS J. CLAPP, OF CLAREMONT, NEW HAMPSHIRE, ASSIGNOR TO SULLIVAN MACHINERY COMPANY, A CORPORATION OF MASSACHUSETTS

COMPRESSOR CONTROLLING MECHANISM

Application filed August 20, 1928. Serial No. 300,860.

My invention relates to a controlling mechanism for a compressor. More particularly, the invention relates to a mechanism for controlling the loading and unloading 5 of a compressor. The principles of my invention may with advantage be employed in a mechanism adapted automatically to unload a compressor so that its driving motor may start without having to drive a fully 10 loaded compressor.

One object of my invention is to provide an improved controlling mechanism for the loading and unloading of a compressor. A further object of my invention is to combine 15 with the electrical connections of an electric motor which drives a compressor improved mechanism for holding the compressor unloaded until the motor has been started. Other objects and advantages of the invention will be clearly apparent from the 20 following description, and more particularly pointed out in the claims.

An illustrative embodiment of the invention is shown in the drawing, of which, 25 Fig. 1 is a diagrammatic view showing the compressor and motor in side elevation, and including a diagram of the electrical connections for the motor.

Fig. 2 is a side elevation of the solenoid 30 which, according to this illustrative embodiment, controls a spring which forms a part of the pilot valve mechanism for controlling unloading of the compressor. In this view the cover is broken away to expose the solenoid and pilot valve.

Fig. 3 is a section on line 3—3 of Fig. 4. Fig. 4 is a section on line 4—4 of Fig. 2.

In Fig. 1 there is shown an electric motor 8 driving a compressor 9. Although it 40 will be understood that my invention is applicable to any of the usual types of compressors, there is disclosed herein a compressor of the vertical, two cylinder type, which is provided with suitable pistons and 45 inlet and discharge valves. The fluid being pumped may be air; and in such case, the same is drawn in through an air filter 10. The fluid being pumped is discharged from the compressor through a suitable pipe connection (not shown) to a receiver tank 11,

from which it may be supplied for any desired purpose. I have illustrated a simple three-pole switch 12 for controlling the supply of current to the motor which, in this instance, may be three-phase, alternating 55 current from the lines 13, 14 and 15. This starting switch is connected with a solenoid 16 and the motor may, if desired, be started and stopped automatically in accordance with pressure conditions in the receiver tank 60 11. The current through the solenoid 16 is under the control also of a manually operable switch, so that the operator may himself control the starting and stopping of the motor. A switch 17 is also provided, as is 65 customary, so that the connection with the outside source of power may be made or broken at any time by the operator.

A suitable pressure operated switch 18 is connected by a pipe 19 to the receiver 70 tank 11. As pressure switches of this type are well known in the art, the details of the same have not been illustrated herein. Preferably a switch will be selected which will open and close within the desired limits of 75 pressure, closing a circuit when the desired minimum pressure is reached and breaking it when the maximum is attained. The pressure switch 18 is included in a control circuit 19' to which energy is supplied from 80 the main line through a small transformer 20. This control circuit includes the solenoid 16 and accordingly the flow of current through the solenoid 16 may be controlled 85 by the pressure switch 18. In the embodiment illustrated in Fig. 1 the solenoid 16 operates when energized to connect the motor with the main line. Accordingly, when receiver pressure lowers to the minimum desired, the switch 12 is closed and motor 8 90 started, and when the maximum is reached the switch 12 is opened and the motor stopped.

The above described operation of the control circuit occurs when the switch 21 (of 95 the manually operable type) is closed. Should, however, it be desired to manually control the solenoid 16, a second manually operable switch 22 may be closed to energize the solenoid 16. It will be noted that 100

the switch 22 is connected in parallel with the pressure switch 18. Various combinations of manual and automatic control for the solenoid 16 will be obvious from the 5 above description of this control circuit.

The mechanism employed for unloading and loading the compressor may be of the type disclosed in Fig. 4 of my Patent No. 1,657,200, dated January 24, 1928, to which 10 reference should be had for a fuller description of the mechanism.

Only general features of the pilot valve shown in Figs. 2 and 3 will be described herein, as a full description of this pilot 15 valve may be found in the patent to Conrader, No. 1,601,943, dated October 5, 1926. A pipe 23 supplies fluid under pressure from the receiver tank to the pressure chamber 46 of the pilot valve mechanism 24. A movable valve member 47 within the pilot valve mechanism 24 is adapted, in one position, to supply pressure fluid through the connection 25 to the compressor unloading mechanism, and, in another position, to vent the 20 connection 25 to atmosphere. A pin 28, associated with said movable member 47 in a supporting relation, projects through the end of the casing of the pilot valve mechanism 24 and bears against a lever 26. A spring 27, when under tension, pulls the lever 26 against said pin 28. A loop 29 at one end of said spring engages one of a plurality of serrations in the lever 26. A loop 30 at the other end of the spring 27 engages 25 a notch in a screw 31 which projects through a yoke 32. A nut 33 holds the screw 31 in adjusted position and permits adjustment thereof. The yoke 32 has a pair of long arms 34 braced by a rivet 35 and sleeve 45, 30 and secured to the core 36 of a solenoid 37. A circuit 38, connected at 40 and 41 to two of the main line connections for the motor, supplies current to energize the solenoid and force the core 36 to the left. A time delay 35 relay 39 is interposed in the circuit 38 to cause a predetermined interval of time to elapse between the beginning of current flow through the main line and the energizing of the solenoid 37. It will be noted that the 40 operating devices for the time relay 39 are energized by a circuit in parallel with the solenoid 37 and deriving current from the conductors connected at 40 and 41 to two of the main power connections for the 45 motor.

Whenever the switch 12 is open, the solenoid 37 is de-energized, and the spring 27 does not perform its function of holding the lever 26 firmly against the pin 28. A free 50 passage is therefore afforded the fluid in the receiver to pass through pipes 23 and 25 to the unloading mechanism to hold the compressor unloaded. Therefore, the compressor is always unloaded when the motor is not 55 running. It should be noted that when

pressure in the receiver 11 falls so low that the unloading mechanism is not actuated, the compressor is in effect unloaded because there is no substantial pressure against which the piston of the compressor needs 70 act.

Assuming that the motor 8 is started up, either due to the closure of the automatic pressure switch 18, or to closure of the manually operable switch 22, then the time delay relay is set in operation; and as the predetermined interval elapses, the solenoid 37 is energized so as to force the core 36 to the left and apply the proper spring pressure to the lever 26. Should the pressure in 80 the receiver 11 be low, the pilot valve 24 will function to load the compressor by venting pressure fluid from the pipe connection 25.

Assuming that the compressor is running, and that the switch 21 is closed and the switch 22 open, the solenoid 16 is now under the control of the automatic pressure switch 18. Should the pressure in the receiver 11 exceed the pressure for which the switch 18 is set, current will be cut off from 90 the solenoid 16 to disconnect the motor from the main line. Immediately the solenoid 37 is de-energized, and the core 36 moves to the right so as to relieve the pressure exerted by the spring 27. The movable valve member 47 within the pilot valve mechanism 24 is now free to move so as to supply pressure fluid through the connection 25 to unload the compressor, and so moves.

It is therefore apparent that whenever 100 the motor 8 is stopped the compressor is unloaded. When the supply of fluid in the receiver tank 11 has been sufficiently depleted to cause actuation of the automatic switch 18, the supply of current through the control circuit 19 is restored and the solenoid 16 energized so that the switch 12 is closed. The motor is at once started, and after a predetermined time interval, during 105 which the motor 8 is permitted to come up to speed, the solenoid 37 is energized. The pilot valve 24 is now restored to operative condition, and the compressor is again loaded. Whenever the solenoid 16 is to be controlled only by the pressure switch 18, the tension of spring 27 should be so adjusted that the compressor will not unload before the switch 18 opens, and will not fail to reload when the switch 18 closes. By proper adjustment the spring 27 may serve 110 as a safety device, insuring unloading should the device 18 not stop the motor when the maximum desired pressure is reached.

Assuming that the switch 21 is open, the solenoid 16 will be under the control of the manually operable switch 22. By closing this switch the operator may start the motor, since the solenoid will pull the switch 12 into closed position. The motor, however, has sufficient time to come up to speed 115

before loading takes place, since the solenoid 37 is not energized until a predetermined time interval has elapsed. It does not necessarily follow, however, that when the solenoid 37 is energized the compressor is immediately loaded, since the movement of the yoke 32 to the left merely restores the pilot valve 24 to operative condition. The compressor now runs loaded or un-loaded, dependent upon whether the pressure in receiver 11 is sufficient to force the movable member 47 to the right so as to deliver fluid through the connection 25 to actuate the unloading mechanism of the compressor, or whether the spring 27 overcomes the receiver pressure and holds the movable member 47 in the position shown in Fig. 3.

The motor now continues to run so long as the switch 22 is closed; and the compressor is loaded and unloaded automatically through the agency of the pilot valve 24 as the pressure in the receiver tank falls and rises. It is obvious therefore that while the motor is under the control of the manually operable switch 22, the spring 27 may be adjusted so as to cause loading and unloading at such pressures (within the capabilities of the mechanism) as are desired.

My invention improves the efficiency of the compressor, and in an improved manner functions to automatically unload the compressor when the motor is stopped. The solenoid which in this illustrative embodiment is employed in the control system, is so combined with elements of the pilot valve as to insure that this pilot valve can not function to load the compressor during such time as current is cut off from the compressor driving motor.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In combination, a compressor having an unloader adapted in one position to unload and in another position to load said compressor, said unloader being pressure fluid actuated, a driving motor for said compressor, a pilot valve for controlling the supply of actuating fluid to said unloader comprising a valve member adapted in one position to open communication of the supply of actuating fluid to said unloader and in another position to vent the fluid previously supplied, said valve member having means including a surface subject to compressor discharge pressure for normally biasing said

valve member toward unloading position, resilient means for normally biasing said valve member toward loading position, a movable member against which said resilient means reacts, and means for controlling said movable member automatically in accordance with the stopping and starting of said driving motor. 70

2. In combination, a compressor, a driving motor therefor, means for unloading 75 said compressor, a pilot valve responsive to compressor discharge pressure for controlling said compressor unloading means, said pilot valve comprising a movable member having a surface subjected to compressor discharge pressure and resilient means for normally supporting said movable member in opposition to said compressor discharge pressure, a second movable member against which said resilient means reacts, and means 80 for controlling said second movable member automatically in accordance with the stopping and starting of said driving motor. 85

3. In combination, a compressor, an electric driving motor therefor, means for un-loading 90 said compressor, means for controlling said compressor unloading means comprising a movable member having a surface subjected to compressor discharge pressure, resilient means for normally supporting 95 said movable member in opposition to said compressor discharge pressure, and a mem-ber against which said resilient means reacts, said member being movable to supporting position upon flow of current to said 100 compressor driving motor and movable to opposite position when no current is flowing thereto.

4. In combination, a compressor, a driv-ing motor therefor, means for unloading 105 said compressor, means for controlling said compressor unloading means comprising a movable member having a surface subjected to compressor discharge pressure, said mem-ber movable to effect loading and unloading, resilient means for normally supporting 110 said movable member in opposition to said compressor discharge pressure during loaded operation, a solenoid, means whereby said solenoid is controlled automatically in accordance with the stopping and starting 115 of said driving motor, and a second mov-able member actuated by said solenoid and against which said resilient means reacts. 120

5. In controlling mechanism for a motor driven compressor, the combination with a pilot valve comprising a movable member having a surface subjected to fluid pressure, and tending to move the same in one direc-tion, resilient means for normally support-ing 125 said movable member in opposition to said fluid pressure, to render the same responsive to a pressure in excess of a desired maximum, of a solenoid, and a second mov-130

able member actuated thereby against which said resilient means reacts.

6. In controlling mechanism for a motor driven compressor, the combination with a pilot valve comprising a movable member having a surface subjected to fluid pressure tending to move said member in one direction, and means comprising a spring for normally supporting said movable member in opposition to said fluid pressure to render the same responsive to a pressure in excess of a desired maximum, of a solenoid, and a second movable member actuated thereby and cooperating with said spring, said second movable member when in one position maintaining said spring in supporting condition and in another position permitting said spring to relax.

7. In controlling mechanism for a motor driven compressor, the combination with a pilot valve comprising a movable member having a surface subjected to fluid pressure tending to move said member in one direction, and means comprising a lever and a spring for normally supporting said movable member in opposition to said fluid pressure, of a solenoid, and a longitudinally movable member actuated thereby and connected to said spring, said movable member when in one position maintaining said spring in supporting condition and in another position permitting said spring to relax.

8. In combination, a compressor, means for unloading said compressor, a driving motor for said compressor, and means for controlling the loading and unloading of said compressor comprising a movable member whose movements control loading and unloading, said member having a surface subjected to compressor discharge pressure, and resilient means cooperating with said movable member, the compressor discharge pressure tending to move said member in a direction to cause unloading of the compressor and the resilient means tending to move the same in a direction to cause loading of the compressor, a movable member against which said resilient means reacts, and means for controlling said movable member automatically in accordance with the stopping and starting of said driving motor.

9. In combination, a compressor, means for unloading said compressor, a driving motor for said compressor, means for controlling the loading and unloading of said compressor comprising a movable member with a surface subjected to compressor discharge pressure, and resilient means cooperating with said movable member, movements of said member controlling loading and unloading and the compressor discharge pressure tending to move said member in a direction to cause unloading of the com-

pressor and the resilient means tending to move the same in a direction to cause loading of the compressor, pressure responsive means for controlling the stopping and starting of said driving motor automatically in accordance with the variations in the discharge pressure of said compressor, a movable abutment member for said resilient means, and means whereby the position of said abutment member is controlled by stopping and starting of said driving motor.

10. In combination, a compressor, means for unloading said compressor, a driving motor for said compressor, means for controlling loading and unloading of said compressor comprising a movable member with a surface subject to compressor discharge pressure, and resilient means cooperating with said movable member, means governed by movements of said member controlling loading and unloading, the compressor discharge pressure tending to move said member in a direction to cause unloading of the compressor and the resilient means tending to move the same in a direction to cause loading of the compressor, pressure responsive means adapted to control the starting and stopping of said motor automatically in accordance with variations in the discharge pressure of said compressor, manually operable means adapted to start or stop said motor at will, either of said motor controlling means being selectively connectible to said motor to control the same, a movable abutment member for said resilient means, and means whereby the position of said abutment member is controlled by starting and stopping of said driving motor.

11. In combination, a compressor, means for unloading said compressor, an electric motor for driving said compressor, means for controlling loading and unloading of said compressor comprising a movable member with a surface subject to compressor discharge pressure, and resilient means cooperating with said movable member, means governed by movement of said member controlling loading and unloading, the compressor discharge pressure tending to move said member in a direction to cause unloading of the compressor and the resilient means tending to move the same in a direction to cause loading of the compressor, a pressure switch adapted to control the starting and stopping of said motor automatically in accordance with variations in the discharge pressure of said compressor, a manually operable switch adapted to start or stop said motor at will, either of said switches being connectible at will to control said motor, a solenoid having a core member providing an abutment for said resilient means, and means whereby the position of said core is automatically controlled by starting and stopping of said driving motor.

12. A controlling mechanism for a prime mover driven compressor having unloading means, comprising, in combination, means for controlling actuation of said unloading means in accordance with compressor discharge pressure, and means for rendering said controlling means inherently operative automatically in accordance with operation of the prime mover. 5
13. A controlling mechanism for a unit having a prime mover driven compressor provided with unloading means, comprising, in combination, means for controlling actuation of said unloading means in accordance with compressor discharge pressure, and means for rendering said controlling means inherently operative automatically in accordance with normal operation of said unit. 10
14. A controlling mechanism for a unit having a prime mover driven compressor provided with unloading means, comprising, in combination, a pilot valve adapted to be actuated by compressor discharge pressure to effect operation of said unloading means, and means cooperating with said pilot valve for rendering the same inherently operative automatically in accordance with normal operation of said unit. 15
15. A controlling mechanism for a unit having a prime mover driven compressor provided with unloading means, comprising, in combination, a pilot valve adapted to be actuated by compressor discharge pressure to effect operation of said unloading means, and means cooperating with said pilot valve for rendering the same inherently operative automatically in accordance with normal operation of said unit, said latter means including a solenoid adapted 20
- 40 when energized to effect said inherent operativeness of said pilot valve. 25
16. A controlling mechanism for a unit having a prime mover driven compressor provided with unloading means, comprising, in combination, a pilot valve adapted to be actuated by compressor discharge pressure to effect operation of said unloading means, and means cooperating with said pilot valve for rendering the same inherently operative automatically in accordance with normal operation of said unit, said latter means including a solenoid, and a yieldable connection between said solenoid and pilot valve whereby upon energization 30 of said solenoid the inherent operativeness of said pilot valve is effected. 35
17. The combination comprising a unit having a prime mover driven compressor provided with unloading means, mechanism 40 for controlling actuation of said unloading means automatically in accordance with compressor discharge pressure, and means for rendering said controlling mechanism inherently operative automatically in accordance with normal operation of the unit, said 45
- 50 latter means having a device actuated by the supply of power to the prime mover. 55
18. The combination comprising a unit having an electric motor driven compressor provided with unloading means, mechanism 70 for controlling actuation of said unloading means automatically in accordance with compressor discharge pressure, and electrically controlled means for rendering said controlling mechanism inherently operative 75 automatically in accordance with a predetermined condition of the unit. 80
19. The combination comprising a unit having an electric motor driven compressor provided with unloading means, mechanism 85 for controlling actuation of said unloading means automatically in accordance with compressor discharge pressure, and electrically controlled means for rendering said controlling means inherently operative automatically in accordance with a predetermined condition of the unit, said electrically controlled means having provision for being supplied with current from the same source as that from which said electric motor is 90 supplied. 95
20. In a pilot valve mechanism, a movable controlling member having a surface subjected to a pressure to be controlled, said member operative when moved in a predetermined manner to effect a control, resilient means for opposing movement of said member in response to the pressure to be controlled, an element movable to stress said resilient means to render said member inoperative to effect its said control except when predetermined pressure conditions exist, means automatically limiting the stress imposed by movement of said element to the desired amount, and means for moving said 100 element to stress said resilient means. 105
21. In combination with a motor driven pump, controlling mechanism including a controlling member having a surface subjected to pump discharge pressure, said member operative when moved in a predetermined manner to effect a control, resilient means for opposing movement of said member in response to pump discharge pressure, an element movable to stress said resilient means to render said member inoperative to effect its said control except when a predetermined maximum pump discharge pressure exists, means for automatically limiting the stress imposed by movement of said 110 element, and means for moving said element to stress said resilient means only when the compressor is driven at a predetermined speed. 115
22. In a controlling mechanism for a motor driven compressor, the combination with a pilot valve comprising a movable member, variations in whose position determine the operation of said valve, said member having a surface subject to fluid pressure, and re- 120 125
- 60 65 70 75 80 85 90 95 100 105 110 115 120 125

silient means for normally supporting said movable member in opposition to said fluid pressure during normal loaded running of said compressor, of a movable member

5 against which said resilient means reacts, and actuating means for said second mentioned movable member controlled in accordance with the speed of the compressor.

23. In a controlling mechanism for a motor driven compressor, the combination with

10 a pilot valve comprising a movable member having a surface subject to fluid pressure and resilient means for normally supporting said movable member in opposition to said fluid pressure during normal loaded running of said compressor, of a movable member

15 against which said resilient means reacts, and actuating means for said second mentioned movable member controlled in accordance with the speed of the compressor.

20 said second mentioned movable member when in one position maintaining said spring in supporting condition and in another position relieving the stress of the

25 spring.

24. In a controlling mechanism for a motor driven compressor, in combination, in a pilot mechanism, a movable member changes in whose position effect control by

30 said pilot mechanism, said member having a surface subject to fluid pressure, and a spring for normally supporting said movable member in opposition to the fluid pressure, of a second movable member alined

35 with said spring and movable to impose a stress on the latter to cause the same to support the first mentioned movable member in opposition to the fluid pressure, and actuating means for said second mentioned

40 movable member controlled in accordance with the speed of the compressor.

25. In a controlling mechanism for a motor driven compressor, in combination, in a pilot mechanism, a movable member changes

45 in whose position effect control by said pilot mechanism, said member having a surface subject to fluid pressure, and a spring for normally supporting said movable member in opposition to the fluid pressure, of a

50 second movable member alined with said spring and movable to impose a stress on the latter to cause the same to support the

55 first mentioned movable member in opposition to the fluid pressure, and actuating means for said second mentioned movable member controlled by the speed of the compressor including a solenoid energized as

85 the compressor reaches normal running speed.

60 26. In a controlling mechanism for a motor driven compressor, in combination, in a pilot mechanism, a movable member changes

65 in whose position effect control by said pilot mechanism, said member having a surface subject to fluid pressure, and a spring for

normally supporting said movable member in opposition to the fluid pressure, of a sec-

70 ond movable member aligned with said spring and movable to impose a stress on the latter to cause the same to support the first mentioned movable member in opposition to the fluid pressure, and controlling means for said second movable member including a solenoid and means for limiting the movement thereof by said solenoid.

75 27. In a pilot valve mechanism, in combi-

nation, a valve casing having connections for receiver pressure and for a receiver pres- 80 sure actuated unloading device, a valve in said casing controlling communication be- 85 tween said connections, and means for main- 90 taining said valve closed until receiver pres- 95 sure reaches a desired maximum and clos- 100 ing the same upon a predetermined drop be- 105 low said maximum including a solenoid en- 110 ergized during normal controlling opera- 115 tion of said valve continuously both in the open and in the closed positions of the latter.

28. In a pilot valve mechanism, in combi-

nation, a valve casing having connections for a source of pressure to be controlled, to atmosphere, and for a pressure operable un- 110 loading device, valve means for closing com- 115 munication between the first and third connec- 120 tions and opening communication be- 125 tween the second and third when the pres- 130 sure to be controlled is below a desired value and automatically reversing such connec- 135 tions when such value is reached including a solenoid energized during normal control- 140 ing operation of said valve continuously in both of said positions of said valve.

29. In a pressure responsive controlling mechanism for a compressor or the like, in combination, a valve casing having a connec-

100 tion with a source of controlling pressure and a connection to a device to be controlled, a valve in said casing, means for subjecting said valve to said controlling pressure to provide an actuating force therefor, and electro-magnetically controlled means for providing an opposing force adequate to prevent valve movement only until the controlling pressure reaches a desired value and upon the attainment of said value, though still exerted, to be overcome by the valve actuating force.

30. In combination, a pump, a driving motor therefor, said pump having unloading means, and means for controlling actua-

110 tion of said unloading means automatically in accordance with pump discharge pres- 115 sure variations including a solenoid ener- 120 gized continuously both during loaded and 125 unloaded operation of said pump at such speed, when said pump is driven at normal 130 operating speed.

31. In combination, a pump, a driving motor therefor, said pump having unloading means, and means for controlling actua-

tion of said unloading means automatically in accordance with pump discharge pressure variations to control the quantity of fluid delivered by said pump during periods of 5 continuous driving thereof by said motor including a solenoid and means for energizing the same when the pump attains normal operating speed and maintaining the same energized during continued drive of said 10 pump.

In testimony whereof I affix my signature.
